UNITED STATES PATENT OFFICE.

EDMUND I. CUTTER, OF NORWOOD, OHIO, ASSIGNOR TO THE AMERICAN LAUNDRY MACHINERY COMPANY, OF NORWOOD STATION, CINCINNATI, OHIO, A CORPORATION OF OHIO.

DRYING MACHINE.

Application filed June 3, 1921. Serial No. 474,593.

To all whom it may concern:

Be it known that I, EDMUND I. CUTTER, a citizen of the United States, residing at Norwood, in the county of Hamilton and State 5 of Ohio, have invented certain new and useful Improvements in Drying Machines, of which the following is a specification.

This invention relates to improvements in drying machines.

10 More particularly this invention relates to the type of drying machine used in laundries for drying clothes. The objects of this invention are to provide a means for circulating air through a heating chamber and then 15 through a drying chamber by means of the fan or blower to cause the air after leaving the drying chamber to be separated into strata and to separate the strata of air containing the moisture from the strata of dry 20 air so that the moisture-laden stratum can be discharged from the machine and the stratum of dry air re-circulated through the heating chamber and the drying chamber; furthermore to provide means whereby at 25 the conclusion of the drying operation the heating chamber can be cut out and the door of the machine opened to permit cold air to be drawn through the drying chamber and expelled directly through the exhaust. 30 Further objects of this invention will appear from the following description and claims when considered together with the accompanying drawings.

Fig. 1 is a vertical section through a drying machine; Fig. 2 is a transverse section through the plane of line 2—2, Fig. 1, and Fig. 3 is a vertical longitudinal section through the plane of line 3—3, Fig. 1.

The main outer casing 1 of the drying 35 machine comprises the fan or blower chamber 2, the heating chamber 3, and the drying chamber 4. These chambers or compartments are divided off by means of the partition wall 5 which extends throughout the 40 entire length of the machine, the transverse horizontal partition wall 6 which is supported by the wall 5 and the angle iron 7, which extends throughout the entire length of the machine casing, and the wall 8 which 45 extends throughout the entire length of the machine casing and is provided with suitable openings for the screens 9. The wall 8 extends upwardly along the angle iron 7, to which it may be also secured, and has 50 secured to its upper edge the strip 10 which together with the oppositely disposed strip 11, extending throughout the length of the machine, form a throat or outlet from the drying chamber to the discharge passage 12. 55 Doors 13 are hinged at 14 on the wall of the machine casing so that access can be had to the screens 9 whenever desired to clean the lint therefrom.

As will be seen, the partition wall 5 is 60 curved through its upper portion so as to form a drying chamber to accommodate the rotary foraminous cylinder 15 which can be rotated in any suitable manner. The curved strip 1a secured to the inside of casing 1 is so located as to direct the drying medium 65 into the drying chamber. This cylinder is provided with the door 16 through which the materials can be placed in and removed from the cylinder when the door 17 on the machine casing is also opened. The partition wall 18 is secured by means of the joint 70 19 to the outer wall of the casing and has its lower portion bent outwardly to the angle bar 20 secured along the inside face of the casing wall. The partition wall 18 is 75 also given a proper curvature to define the drying chamber. The customary baffles 21 are also provided in the cylinder. As many fans or blowers can be used as necessary or desired, two being here shown, driven by the 80 same shaft 2b with pulley 2c, and the corresponding number of screens 9 will be provided. These fans are of the snail-shell type with a clock-wise direction of rotation, as 85 viewed in Fig. 1, and may be referred to as 90 "over-shot" by analogy to a water wheel. Each fan 2a has the volute 22 which extends to form the passage-way 23, the several passage-ways merging into the larger conduit 23a which communicates with the bottom of the heating chamber when the valve 24 is in the full line or raised position, or with the common discharge 26 when the valve 24 is in dotted line position, as indicated in Fig. 1. Another passage-way 25 leads 95 off from each volute 22 and has communication with the discharge outlet 26 which opens through the side of the casing. A lip 27 is formed upon the edge portion of each wall 28 so as to extend into the path of the strata 100 of air or other drying fluid which is circulated by the fan. This wall 28 is joined at its lower edge portion with the upright wall 29 which extends upwardly to the transverse partition wall 6. The passage-way 110

- 25 is formed by means of the tapering conduit member secured at its larger end to wall 29 by means of flanges and at its smaller end to the volute and the wall 28.
- 5 A valve 24 for all of the fans is mounted on the shaft 30 which is operated by means of the handle 31 extending to the outside of the casing. As will be clear, the several chambers are in communication with each 10 other.
- When the machine is operated for drying materials in the cylinder 15, the doors 16 and 17 are closed and the fan will draw air through the screened openings 33 and circu- 15 lated by means of the passage-ways 23 through the heating chamber 3, the drying chamber 4 and the screens 9 which will catch the lint picked up by the air from the materials in the cylinder, and finally this air 20 will be returned to the fan chamber. Because of the more or less moisture picked up by the air or other drying fluid in its passage through the wet materials, a part of the same will be heavier than the rest which 25 contains less moisture or none at all. Experience has shown that for a constant speed and for the same size of fan, the centrifugal forces generated by the fan are in direct proportion to the weight of the air or other 30 fluid per unit of volume. That is to say, the moisture-laden air, which is heavier than the dry air, will cause a greater force to be generated than the air which contains no moisture. This means that the moisture- 35 laden air coming from the drying chamber will be divided into inner and outer strata with respect to the axis of the fan. The inner stratum will be comparatively dry while the outer stratum will consist of the 40 moisture-laden air. Lip 27 is so positioned that the moisture-laden stratum of air will pass above the same and out through the passage-way 25 to the exhaust, while the lower stratum of comparatively dry air will 45 pass below the lip 27 and through the passage-way 23 to be re-circulated through the machine. In this way I avoid the re-circulation of the moisture-laden air through 50 the machine.
- 50 Upon completion of the drying operation the valve 24 will be lowered to dotted line position against the stops 24^a fixed to the inner wall of the casing, and the door 17 is then opened to permit fresh air to enter and 55 pass through the screens 9 to the fan chamber. This fresh, cold air is then forced out

directly through the exhaust 26 without being permitted to pass through the heating chamber. In this way the materials are cooled sufficiently to permit their removal. 60

The principal advantages resulting from this invention reside in the fact that with this machine only comparatively dry air is re-circulated through the heating and drying chambers and consequently greater efficiency is attained, since for a given temperature of the air for drying, a lower degree of heat is required in the heating chamber and furthermore the heating coils are not subjected to the corrosion due to accumulation of moisture thereupon. Furthermore the drying process is quicker since the dry air possesses a higher degree of drying efficiency than does the moisture-laden air. 70

Further advantages resulting from this invention will be apparent to those who are skilled in the art to which it relates. 75

What I claim is:

1. In a drying machine, the combination of a casing, a compartment therein for materials to be dried, a heating chamber in the rear part of said casing, a rotary fan of snail shell type located in the lower, forward portion of said casing for passing a drying fluid through said chamber and compartment, said fan having an over-shot action and communicating with the bottom part of said heating chamber, and said casing being provided with a discharge leading substantially tangentially from the upper 90 side of said fan to an outlet at the side of said casing. 80

2. In a drying machine, the combination of a casing, a compartment therein for materials to be dried, a heating chamber in the rear part of said casing, a rotary fan of snail shell type located in the lower, forward portion of said casing for passing a drying fluid through said chamber and compartment, said fan having an over-shot action and communicating with the bottom part of said heating chamber, said casing being provided with a discharge leading substantially tangentially from the upper side of said fan to an outlet at the side of said casing, 95 and means for maintaining separate the strata of fluid from the fan to said heating chamber and discharge outlet, respectively. 100

In testimony whereof I hereby affix my 110 signature.

EDMUND I. CUTTER.
